UNITED STATES PATENT OFFICE

WALTER R. SCHLAGE, OF SAN FRANCISCO, CALIFORNIA, ASSIGNOR TO SCHLAGE LOCK COMPANY, OF SAN FRANCISCO, CALIFORNIA, A CORPORATION OF CALIFORNIA

DOOR LATCH

Application filed April 18, 1928. Serial No. 270,815.

This invention relates to a door latch, such as used in French doors, screen doors, etc., and it also relates to a door latch which may be used as a night latch and the like.

5 The object of the present invention is to generally improve and simplify the construction and operation of door latches; to provide a door latch which may be installed in a door with a minimum of skill and effort; to provide a door latch which may be installed in a comparatively thin door, such as a screen door, a French door, etc.; to provide a door latch which is adjustable to take care of doors of varying thickness; to provide a door latch 15 which permits centralization of the bolt or latch with relation to the edge of the door; to provide a door latch which is reversible to take care of right- and left-hand doors; to provide a door latch which consists of two 20 separable units, to-wit, a bolt or latch unit and a latch actuating unit; to provide a door latch structure which permits a rigid interlock between the two units when assembled in a door; to provide an interlock which is 25 simple in construction and which insures proper alignment and co-action between the working parts; and further to provide a door latch which may be key or knob actuated or both, as conditions may demand.

30 The door latch is shown by way of illustration in the accompanying drawings, in which:

Figure 1 is a perspective view of the latch unit,

35 Figure 2 is a perspective view of the latch actuating unit,

Figure 3 is a central vertical longitudinal section of the door latch taken on line III—III, Figure 7,

40 Figure 4 is a horizontal sectional view of a door showing a modified form of the door latch,

Figure 5 is a perspective view of the rollback crank,

45 Figure 6 is a perspective view of the anchor plate,

Figure 7 is a horizontal section of a door showing the latch unit and the latch actuating unit assembled and interlocked in the 50 door,

Figure 8 is a perspective view of the spindle,

Figure 9 is a perspective view of the driver plate,

Figure 10 is a perspective view of the cam plate,

Figure 11 is a perspective view of the washer, whereby the spindle and the driver plate are secured to the cam plate,

Figure 12 is a longitudinal section of the 60 inner end of a key-actuated tumbler lock showing the cam plate, the driver plate and the spindle secured to the cylinder plug,

Figure 13 is an end view of the key-actuated tumbler lock. 65

Referring to the drawings in detail and particularly Figures 1, 2, 3 and 7, A indicates in general the latch actuating unit, B the latch unit and C the door in which the units are assembled. The latch unit consists of a 70 latch face plate 2 which may be secured to the edge of the door in the usual manner as by means of screws, such as shown at 3. Secured to the rear side of the latch plate is a latch housing 4. The housing illustrated 75 in the present instance is cylindrical in cross-section and it forms a guide for the bolt or latch 5, a latch bar 6 secured thereto, and a spring 7 whereby the latch is normally projected. The rear end of the latch housing 80 is closed by an end section 8 and this end section is reinforced and strengthened by an end plate 9. Extending through the end section 8 and the plate 9 is an anchor plate 10. This plate is best illustrated in Figure 6. 85

The inner end of the anchor plate is provided with a shank 11 which extends through the plates 8 and 9 and it is riveted or otherwise secured thereto. The inner end of the latch bar 6 also extends through the plates 8 and 9 and pivotally attached to the latch bar as at 11 is a rollback crank generally indicated at 12, this crank being best illustrated in Figures 1, 3 and 5. The rollback crank consists of two web members, as shown, which are tied 95 together at the bottom by a cross piece 13. The lower ends of the webs are slotted, as shown at 14, to receive a spindle bar 15, as will hereinafter be described. The upper ends of the webs are perforated to receive 100

the pivot pin 11 and the inner end of the latch bar is vertically slotted to take care of the aircular movement of the rollback crank. The several members of the latch unit, to-wit, the 5 plate 2, the housing 4, the anchor plate 10, the rollback crank 12 and the latch bar 6 are all permanently attached and connected, as shown in Figure 1, and when so assembled and connected, it can be readily and quickly 10 assembled in a door. An ordinary door, by the way, in order to be prepared for the re-ception of the latch unit and the latch actu-ating unit need only have two holes bored therein, one hole such as indicated at D which 15 passes transversely through the door and a second hole, such as indicated at E, which is disposed at right angles thereto, it being drilled or bored through the edge of the door. After the holes are drilled the latch unit is 20 first inserted in the hole E and is there se-cured by means of the screws 3. The latch actu-ating unit is then inserted from opposite sides of the hole D and when secured, as will hereinafter be described, completes the in-25 stallation and assembly of the mechanism.

The latch actuating unit may be key or knob actuated, i. e., the spindle bar 15 may be rotated either by an ordinary key mechanism or by knobs or handles, such as indicated at 30 16 in Figures 4 and 7. In the present instance both forms are illustrated. By referring to Figures 2 and 7 it will be noted that a pin tumbler type of key actuated lock is illus-trated. This lock consists of a cylinder 17 35 and an exterior escutcheon face plate 18. Mounted interior of the cylinder is the usual cylinder plug and tumblers and secured to the outer end of the cylinder plug is a cam plate 19 which may be rotated when the proper key 40 is inserted, such as shown at 20a in Figure 7. The cam plate in this instance is best illus-trated in Figures 2 and 10 and it cooperates with a driver plate 20 (see Figure 9) to rotate the spindle bar 15 (see Figures 2 and 8). 45 The assembly of the cam plate, the driver plate and the spindle is best shown in Figure 12, i. e., the cam plate is secured by means of screws 21 and lugs 22 to the inner end of the cylinder plug. The driver plate 20 is po-50 sitioned exterior of the cam plate and it is provided with an annular flange 22a which terminates in a pair of opposed shoulders 23 and 24. The inner end of the spindle bar 15 passes through a slot 25 in the driver plate 55 and as this slot has the same cross-sectional shape as the spindle bar, an interlock to pre-vent rotation is formed. The cam plate 19, on the other hand, is provided with a round central opening 26 through which the inner 60 end of the spindle bar passes so that the cam plate may be turned independently thereof. The inner face of the cam plate is also re-cessed, as shown at 27, to receive a washer 28. The inner end of the spindle bar is riveted to 65 this washer, as shown at 29 (see Figure 12)

and the driver plate is thus secured to the cam plate, but the cam plate is free to rotate a given distance without rotating the driver plate, i. e., the cam indicated at 19a which is carried by the cam plate can rotate freely be-tween the shoulders 23 and 24 and it does not transmit movement to the driver plate until one or the other of the shoulders is engaged. The normal position of the lug 19a is central-70 ly between the shoulders 23 and 24. This is 75 im-70 portant as it permits the knob or handle 16 to rotate the spindle 15 without interfering with the cam plate or the key-actuated mech-anism. On the other hand, when the key is inserted, the cam plate is rotated until lug 19a 80 engages one of the shoulders and the driver plate together with the spindle is then rotated thereby. By referring to Figure 7 it will be noted that the spindle bar 15 projects into the knob or handle 16, i. e., it fits a rectangu-85 lar-shaped slot formed therein and it is ac-cordingly possible to rotate the spindle either by the knob or the key-actuated cam plate and the driver plate cooperating therewith, and it is also possible to rotate the spindle bar by 90 means of the knob or handle 16 without in-terferring with the cam plate. It makes no difference whether the spindle bar is rotated by the key mechanism or by the knob or handle 16. In either instance rotation of the 95 spindle causes the rollback to swing in the direction of arrow a (see Figure 3). This causes retraction of the retractor bar and the latch 5 and compression of the spring 7; thus permitting opening of the door. On the 10 other hand, when either the key or the knob is released, the spring will extend and the parts will move back to normal position. 105 One of the important features of the pres-ent invention is the method and mechanism 110 employed for interlocking the latch unit and the latch actuating unit. This is accom-plished as follows:

By referring to Figure 2 it will be noted 115 that the cylinder barrel 17 is provided with two posts, such as shown at 30 and 31. The outer ends of these posts are drilled and tapped, as indicated at 32 and they serve the function of receiving the securing screws indicated at 33 (see Figure 7). The anchor 115 plate is perforated, as at 30a, to receive the post 30 and it is notched, as shown at 31a, to receive the post 31. In other words, when installing and assembling the latch mecha-nism, the latch unit B is first inserted end-120 wise through the opening E, the unit, shown in Figure 2, is then inserted through the opening D and when so inserted the spindle bar 15 passes through the slots 14 of the rollback crank while the posts 30 and 31 pass through the respective openings 30a and 31a in the anchor plate, the escutcheon plate, indicated at 35 is applied to the opposite face of the door, and the screws 33 are inserted and secured. This completes the assembly and 130

installation of the latch mechanism. It is, of course, understood that the knob 16 has a rectangular hollow opening formed therein, as indicated by dotted lines at 37, and that this opening receives the free end of the 5 spindle bar as previously described.

The interlock formed by the posts 30 and 31 and the anchor plate is exceedingly important. First of all it is simple; secondly, it forms a rigid interlock between the two 10 units; third, it provides an adjustment which takes care of doors of varying thickness; fourth, it permits centralization of the latch unit B with relation to the edge of the door as the interlock between the posts 30 and 31 15 and the anchor plate is laterally adjustable, i. e., the anchor plate may assume any position required between the outer ends of the posts 30 and 31 and their inner ends, the position assumed depending entirely upon 20 the thickness of the door 5. The rigid interlock formed insures perfect alignment and co-action of the working parts.

The mechanism as a whole is exceedingly simple and as such will not require skilled mechanics when installing and assembling the same. While Figures 1, 2, 3 and 7 illustrate a key-actuated mechanism on one side of the door and a knob mechanism on the 25 other, it is obvious that knobs may be employed on both sides, for instance as shown in Figure 4. The spindle may be square or flat in cross-section, as desired. The spindle shown at 40 is square in cross-section and the opening in the lower end of the rollback crank 30 would then be the same. The spindle would be secured to the handle 16 while the opposite handle 16a would merely be provided for the recess such as shown at 41 for its reception. The handle 16 and the spindle 40 would be 35 permanently attached to the outer escutcheon while the handle 16a only would be permanently secured to the inner escutcheon plate; otherwise the mechanism would be identical to that illustrated in Figures 1, 2 and 3, i. e., the same or identical latch unit B would be 40 employed and the outer escutcheon plate would carry the screw posts 30 and 31, while the inner escutcheon plate would carry the 45 securing screws 33.

Another important feature to be noted is the fact that the key-actuated unit to which the posts 30 and 31 are secured may be inserted through the anchor plate from either 50 side of the door. This fact renders the latch unit, as a whole, reversible and as such permits installation in right- and left-hand doors, as the case may be.

While certain features of the present invention are more or less specifically described, 55 I wish it understood that various changes may be resorted to within the scope of the appended claims; similarly, that the materials and finishes of the several parts employed may be such as the manufacturer may 60

decide or varying conditions or uses may demand.

Having thus described my invention, what I claim and desire to secure by Letters Patent is:—

1. In a door latch of the character described, a latch unit and a latch actuating unit, an anchor member secured on the inner end of the latch unit, and a post-like member on the latch actuating unit extending 70 through the anchor plate and forming an interlock therewith when the two units are assembled in a door.

2. In a device of the character described, a latch housing, a latch projecting through the outer end thereof, an anchor plate secured to the inner end of the latch housing, a latch bar connected with the latch and projecting through the inner end of the latch housing, and a rollback crank pivotally attached to 80 the inner end of the latch bar.

3. In a device of the character described, a latch housing, a latch projecting through the outer end thereof, an anchor plate, secured to the inner end of the latch housing, 90 a latch bar connected with the latch and projecting through the inner end of the latch housing, a rollback crank pivotally attached to the inner end of the latch bar, said rollback crank being perforated to receive a 95 spindle bar and said anchor plate being perforated to receive interlocking members, a latch actuating unit disposed at right angles to the latch unit and the anchor plate, a spindle bar on the latch actuating unit, and a 100 pair of posts on the latch actuating unit, said spindle bar extending through the rollback crank and the posts through the anchor plate when the two units are assembled in a 105 door.

4. In a device of the character described, a latch housing, a latch projecting through the outer end thereof, an anchor plate secured to the inner end of the latch housing, a latch bar connected with the latch and projecting through the inner end of the latch housing, a rollback crank pivotally attached to the inner end of the latch bar, said rollback crank being perforated to receive interlocking members, a latch actuating unit disposed at right angles to the latch unit and the anchor plate, a spindle bar on the latch actuating unit, a pair of posts on the latch actuating unit, said spindle bar extending through the rollback crank and the posts 110 through the anchor plate when the two units are assembled in a door, and means for imparting a rotary movement to the spindle bar.

5. In a device of the character described, 125 a cylinder barrel, a cylinder plug, key-actuated means for imparting rotary motion to the cylinder plug, a cam plate secured to the cylinder plug, a driver plate secured to the cam plate and partially rotatable independ- 130

ently of the cam plate, the cylinder plug and the cam member on the cam plate and engageable with the driver plate to rotate the same, a spindle bar secured to the driver plate, and a pair of posts secured to the cylinder barrel and parallel with the spindle bar.

6. In a device of the character described, a spindle bar, escutcheon plates at opposite ends thereof forming a support for the spindle bar, means connected with opposite ends of the spindle bar for rotating the same, a pair of posts connected with one escutcheon plate, said posts being threaded at their opposite ends, screws extending through the opposite escutcheon plate and engaging the threaded ends of the posts to secure the escutcheon plates to opposite faces of a door, a latch unit extending through the edge of the door at right angles to the spindle bar, means actuated by rotation of the spindle bar for retracting the latch in the latch unit, and an anchor plate on the inner end of the latch unit and interlocking with the posts.
25. 7. In a device of the character described, a spindle bar, escutcheon plates at opposite ends thereof forming a support for the spindle bar, means connected with opposite ends of the spindle bar for rotating the same, a pair of posts connected with one escutcheon plate, said posts being threaded at their opposite ends, screws extending through the opposite escutcheon plate and engaging the threaded ends of the posts to secure the escutcheon plates to opposite faces of a door, a latch unit extending through the edge of the door at right angles to the spindle bar, a latch in the latch unit, a latch bar connected with the latch at one end and with the rollback member at the other end, means actuated by rotation of the spindle bar for rotating the rollback to retract the latch, and anchor means on the inner end of the latch unit through which the posts extend to form an interlock between the latch actuating unit and the latch unit.

8. In a device of the character described a latch housing, a latch projecting through the outer end thereof, an anchor plate on the inner end of the housing, said plate having a plurality of perforations formed therein, a spindle projecting through the anchor plate, a connection between the spindle and latch whereby the latch is reciprocated during rotation of the spindle, and an interlocking member extending through the anchor plate.

9. In a device of the character described, an escutcheon plate, a cylinder barrel mounted in said plate, a cylinder plug in said barrel, key actuated means for imparting rotary movement to the cylinder plug, a pair of lugs formed one on each side of the cylinder barrel, and a post member secured to each lug.

65 WALTER R. SCHLAGE.
